UNITED STATES PATENT OFFICE.

NICHOLAS G. BALLARD, OF CHICAGO, KENTUCKY

TIE-PLATE AND ANTISPREADING DEVICE.

1,242,311.

Specification of Letters Patent.

Patented Oct. 9, 1917.

Application filed August 22, 1916. Serial No. 116,307.

To all whom it may concern:

Be it known that I, NICHOLAS G. BALLARD, a citizen of the United States, residing at Chicago, in the county of Marion and State of Kentucky, have invented certain new and useful Improvements in Tie-Plates and Antispreading Devices, of which the following is a specification.

This invention relates to an improved rail attachment and the principal object of the invention is to provide a structure which can be connected with the rails and ties of a track to hold the rails in place and prevent the rails from having transverse movement and to further hold the ties in the proper spaced relation.

Another object of the invention is to provide a device of the character described which may be easily and quickly put in place and which does not require any special construction of rail or tie.

This invention is illustrated in the accompanying drawings, wherein:—

Figure 1 is a view in top plan showing a section of a track provided with the improved structure.

Fig. 2 is a sectional view taken along the line 2—2 of Fig. 1.

Fig. 3 is a sectional view taken along the line 3—3 of Fig. 1.

Fig. 4 is a view similar to Fig. 2 looking in the opposite direction from Fig. 2.

Fig. 5 is a plan view of one of the tie plates forming part of this structure.

The rails 10 extend longitudinally of the track bed and rest upon the tie plates 20 which tie plates are positioned adjacent the outer ends of the ties 11 and are provided with arms or hooks 25 extending beyond the sides of the ties. Yokes 24 extend along the side faces of these ties and are provided in their end portions with openings to receive the hooks 25, a securing key being passed through one of the hooks as shown in Fig. 4 to assist in holding the yoke in place. It will thus be seen that a substantial structure will be provided consisting of the tie plates upon which the rails rest and the yokes extending along the sides of the ties and having their end portions connected with the arms or hooks 25 of the tie plates. In order to hold the tie plates in place upon the ties, these plates have each been provided with penetrating prongs 26 which will be driven into the tie and have further been provided with ribs 22 which will bite into the ties and

serve to prevent the plates moving longitudinally of the ties. Cleats 23 are positioned upon the upper faces of these plates and engage the outer portions of the rail bases to prevent the rails from moving outwardly or spreading.

In order to hold the ties the proper distance apart, and further to brace the rails against transverse movement, there have been provided bracing plates 12 which extend between the ties and are provided with arms 13 resting upon the tie plates and extending along the inner edge faces of the bases of the rails. Securing spikes 14 will be driven through openings formed in the arms 13 and through the openings 21 of the tie plates and will engage the bases of the rails, the spikes not only serving to hold the bracing plates in position but further serving to engage the rails and together with the cleats 23 serving to hold the rails in place. It should be noted that as the arms extend along the inner edges of the rail bases, they will prevent the rails from moving inwardly.

In order to brace the rails against spreading, there have been provided draw bars 15 which extend through openings formed in the bracing plates 12 and are provided at their outer ends with arms 16 extending beneath the rails and terminating in heads or blocks 17 engaging the outer faces of the webs of the rails as shown in Fig. 2. The inner end portions of these draw bars are formed into threaded pins 18 connected by the turn buckle 19 through the medium of which the draw bars may be properly adjusted to brace the rails against outward spreading movement. This structure will securely hold the rails against spreading movement and against inward movement and will further hold the ties the proper distance apart.

When laying the track, the ties will be put in place and after the tie plates have been placed upon the ties, and connected by the yokes 24, the rails will be put in place and fitted against the cleats 23. The bracing plates will then be positioned between the ties and secured by the fasteners 14 which fasteners will not only hold the bracing plates in position but also engage the rails to hold the rails in place. The draw bars 15 will then be passed through the openings in the bracing plates with their outer end portions engaging the rails and the turn buckles will be adjusted to tighten the draw bars the proper amount. The draw bars

bracing plates and side plates will thus be connected forming a unitary structure serving to hold the ties and rails in place.

What is claimed is:—

- 5 1. A structure of the character described comprising rails positioned in spaced relation, supporting ties for said rails, tie plates positioned upon said ties beneath the rails and in engagement with the rails, yokes connecting said tie plates and extending along the sides of the ties, bracing plates extending between said ties and having their end portions resting upon said tie plates, fasteners passing through the bracing plates and tie plates, draw bars passing through the bracing plates and engaging the outer side faces of said rails, and a turn buckle adjustably connecting the inner ends of said draw bars.
- 10 2. A structure of the character described comprising rails positioned in spaced relation, supporting ties for said rails, tie plates positioned upon said ties beneath said rails, rail engaging means carried by said tie plates for engaging the outer portions of the bases of said rails, bracing plates extending between said ties and having their end portions overlapping said tie plates, fasteners passing through the bracing plates and tie plates and engaging the inner portions of the bases of said rails, draw bars slidably passing through said bracing plates and engaging the outer side faces of said rails, and means adjustably connecting the inner end portions of said draw bars.
- 15 3. A structure of the character described comprising rails positioned in spaced relation, supporting ties for said rails, tie plates fitting upon said ties beneath said rails, bracing plates positioned between said ties and extending in overlapping relation to the tie plates, fasteners passing through the bracing plates and tie plates, draw bars slidably carried by said bracing plates and

engaging the outer faces of said rails, and means adjustably connecting the inner end portions of said draw bars.

4. A structure of the character described including rails positioned in spaced relation, supporting ties for said rails, tie plates resting upon said ties beneath said rails, yokes connecting said tie plates and extending along the sides of said ties, bracing plates extending between said ties, draw bars slidably carried by said bracing plates, and engaging said rails, and means adjustably connecting the inner ends of said draw bars.

5. A structure of the character described including rails, supporting ties for said rails, tie plates resting upon said ties beneath said rails, rail securing means carried by said tie plates, engaging hooks extending from said tie plates, and yokes extending along the sides of the ties and having their end portions provided with openings receiving the engaging hooks to connect the yokes with the tie plates.

6. A structure of the character described comprising rails, supporting ties for said rails, tie plates resting upon said ties beneath said rails, means connecting the tie plates to hold the same against movement toward the ends of the ties, bracing plates extending between said ties and having their end portions connected with the tie plates, the bracing plates engaging the inner side edges of the bases of said rails, draw bars slidably carried by said bracing plates and engaging the outer faces of the rails, and means adjustably connecting the inner end portions of the draw bars.

In testimony whereof I affix my signature in presence of two witnesses,

NICHOLAS G. BALLARD.
